US0D1058571S

(12) **United States Design Patent** (10) **Patent No.:** **US D1,058,571 S**
(45) **Date of Patent:** **** Jan. 21, 2025**

(54) **SUPPORT FOR ELECTRIC DEVICES**

(71) Applicant: **Jiajia He**, Liuzhou (CN)

(72) Inventors: **Jiajia He**, Liuzhou (CN); **Chenglan Huang**, Liuzhou (CN)

(73) Assignee: **Jiajia He**, Liuzhou (CN)

(**) Term: **15 Years**

(21) Appl. No.: **29/883,533**

(22) Filed: **Jan. 31, 2023**

(30) **Foreign Application Priority Data**

Aug. 3, 2022 (CN) 202230502694.4

(51) **LOC (15) Cl.** **14-99**

(52) **U.S. Cl.**

USPC **D14/447**

(58) **Field of Classification Search**

USPC D6/308; D14/305, 306, 307, 336, 371, D14/373, 374, 375, 376, 388, 389, 432, D14/125, 126, 127, 314, 379, 129, 448, D14/449, 450, 451, 452, 132, 217, 239, D14/339, 340, 356, 377, 378, 380, 315, D14/316, 322, 334, 335, 447, 251, 252, D14/253, 440

(57) **CLAIM**

The ornamental design for a support for electric devices, as shown and described.

DESCRIPTION

FIG. 1 is a perspective view of a support for electric devices embodying the new design;

FIG. 2 is another perspective view of the support for electric devices;

FIG. 3 is a front view thereof;

FIG. 4 is a back view thereof;

FIG. 5 is a side view thereof;

FIG. 6 is another side view thereof;

FIG. 7 is a top view thereof; and,

FIG. 8 is a bottom view thereof.

1 Claim, 8 Drawing Sheets
